UNITED STATES PATENT OFFICE.

WILLIAM L. HAAG, OF LANSING, MICHIGAN.

DRIVER FOR ANCHOR-PLATES.

1,135,013.

Specification of Letters Patent. Patented Apr. 13, 1915.

Application filed June 21, 1913. Serial No. 775,026.

To all whom it may concern:

Be it known that I, WILLIAM L. HAAG, a citizen of the United States of America, residing at Lansing, in the county of Ingham and State of Michigan, have invented certain new and useful Improvements in Drivers for Anchor-Plates, of which the following is a specification, reference being had therein to the accompanying drawings.

10 This invention relates to a ground anchor for stay wires or cables and driver for placing the same.

The object of the invention is to provide an anchor which may be driven into the ground with a stay wire attached thereto and when strain is put upon the stay wire, will be turned thereby into a position to firmly engage the earth and prevent its being pulled out by heavy strain put upon 20 the stay.

It is also an object of the invention to provide suitable means for positioning the anchor which means may be driven into the ground with the anchor held thereon and 25 may then be pulled out leaving the anchor embedded in the earth at the desired depth.

A further object of the invention is to provide certain new and useful features in the construction of the anchor and driver, 30 all as hereinafter more fully described.

To these ends the invention consists in the matters hereinafter set forth and more particularly pointed out in the appended claims, reference being had to the accompanying drawing in which—

Figure 1 is a side elevation of a driver with an anchor in section in place thereon illustrating the manner in which they are driven into the ground; Fig. 2 is a similar 40 view with the driver removed; Fig. 3 is a detail illustrating the position of the anchor in use; Fig. 4 is an elevation of the driver with the anchor in place thereon; Fig. 5 is a transverse section of Fig. 4 on the line y—y; Fig. 6 is a perspective view of the anchor 45 detached; Fig. 7 is a perspective view illustrating means for pulling the driver from the ground; and Fig. 8 is an enlarged detail of the upper end of the driver bar and 50 pinch ring thereon.

In providing anchors for the stay wires of telephones, telegraph poles, buildings and other structures it has been the common practice to dig a hole in the ground, place 55 the anchor with the wire or cable attached thereto in the bottom of the hole and then

fill up the hole, but in so positioning the anchor the ground is disturbed and is more or less loose above the anchor so that when a heavy strain is put upon the stay wire the anchor is liable to be pulled out of the ground unless a great deal of care is taken to tamp the ground down in the hole and in many instances it is necessary to weight the anchor by placing stone or other heavy 60 articles thereon within the hole.

In applicant's construction a plate 1 of suitable size and form is driven into the ground edgewise by means of a suitable driver comprising a bar 2 which is suitably 65 formed at its lower end to engage and hold the plate while said plate is being driven into the ground by means of the driver. This plate is preferably substantially rectangular in form and is concave at its lower 70 side and convex at its upper side with a center hole 13 through which the stay wire or cable 3 is passed and made fast to the plate by forming a knot on the end of the wire at the under or concave side of the 75 plate. The bar 2 is formed with a flattened lower end portion 4 having a pointed end 5 so that it may be driven into the ground easily and the flat upper side of this lower end portion forms a seat for the anchor 80 plate, said plate resting thereon at two diametrically opposite corners which corners are preferably cut away to form a straight edge to engage the seat. At the point where the bar 2 merges into the flattened end portion, said bar is formed with an undercut 85 groove 6 to receive the edge of the plate, said groove forming a firm seat for the plate so that when the bar is driven into the ground with the plate engaged therewith, 90 said plate will be forced edgewise into the earth. To hold the plate against lateral movement upon its seat on the flat side of the bar, a lug 7 is formed on the bar to engage a slot 8 in the plate, the upper side 95 of the lug being tapered or cut away so that it will readily withdraw from the slot when the bar or driver is pulled out of the ground by means of a pinch ring 9 which slides freely upon its upper end and is 100 adapted to tilt thereon and grip the bar when it is actuated by means of a suitable 105 pry or lever 10 placed through an opening in an ear 11 on the ring.

After the driver with the anchor plate in 110 place thereon has been driven into the ground as shown in Fig. 1, and the driver

has been removed as shown in Fig. 2, when a strain is put upon the stay wire 3, the tendency of the anchor plate will be to turn within the ground to a position at right angles to the direction of strain upon the stay wire by reason of the attachment of the wire to the center of the plate at one side thereof and the concavo-convex form of the plate. The two laterally extending corners of the plate which project at right angles to the line of strain upon the stay wire also tend to cause the plate to turn in the ground and if found desirable the plate may be provided with spring fingers 12 which are secured to the under concave side of the plate and curved outwardly and laterally therefrom at each side of the driver and extend beyond the upper edge of the plate. These spring fingers offer no material resistance to the driving of the plate into the ground as they will straighten out as they come into engagement with the earth, but after the driver has been removed and a strain is put upon the stay wire, these fingers curving outwardly away from the plate in the direction of the line of pull upon the stay wire, will dig into the earth at the upper edge of the plate thus offering an additional resistance at that edge to the pulling of the plate from the ground. The turning of the plate within the ground is therefore made positive by the use of these fingers.

By driving the anchor plate into the ground edgewise the earth is disturbed but slightly and after the plate has turned within the ground by pulling upon the stay wire it will have a firm hold upon portions of the ground which are in their natural condition. An anchor plate of small dimensions may, therefore, be used and the driving of the plate into the ground greatly facilitates the anchoring of it. Obviously the anchor plate

may be made of any desired size and form with the spring fingers attached thereto or a plain plate used, as desired. The driver 45 may also have other forms than that shown and other changes may obviously be made in the construction and arrangement of parts without departing from the spirit of the invention and I therefore do not limit myself 50 to the form or arrangement shown.

Having thus fully described my invention what I claim is:—

1. A driver for an anchor plate, comprising a bar having a flattened lower end portion to accommodate a plate, said flattened lower end portion being cut away to provide opposed seats for the lower end of said plate, said flattened lower end portion having the upper end thereof undercut to provide a groove to receive the upper end of said plate, and a lug on the flattened lower end portion of said bar adapted to engage the plate. 55

2. A driver for an anchor plate, comprising a bar having a flattened lower end portion terminating in a point, said flattened lower end portion adapted to accommodate a plate and provide a seat for the lower end thereof, said bar at a point where it merges 70 into the flattened end portion having an undercut groove to accommodate the upper end of said anchor plate, and a lug on the flattened lower end portion of said bar adapted to engage in said plate, said lug having the 75 upper end thereof tapered whereby it can be readily withdrawn from the plate.

In testimony whereof I affix my signature in presence of two witnesses.

WILLIAM L. HAAG.
